[57] CLAIM

The ornamental designs for a Combined CPR prompt device and base, as shown and described.

DESCRIPTION

FIG. 1 is a front elevational view of a CPR prompt device, showing our new design without the base;

FIG. 2 is a front elevational view of a second embodiment of the CPR prompt device;

FIG. 3 is a front elevational view of a third embodiment the CPR prompt device;

FIG. 4 is a perspective view of FIG. 1;

FIG. 5 is a rear view of FIGs. 1-4;

FIG. 6 is a side elevational view thereof;

FIG. 7 is a side elevational view thereof; opposite that shown in FIG. 6;

FIG. 8 is a side elevational view of FIG. 2;

FIG. 9 is a top end view of FIGs. 1-4;

FIG. 10 is a bottom end view of FIGs. 1 and 4;

FIG. 11 is a rear elevational view of the base piece to be attached to the bottom of FIGs. 1-4;

FIG. 12 is a front elevational view thereof;

FIG. 13 is a side elevational view thereof;

FIG. 14 is a side elevational view thereof, opposite that shown in FIG. 13;

FIG. 15 is a top end view thereof;

FIG. 16 is a bottom end view thereof;

FIG. 17 is a top end view of the CPR prompt device of FIGS. 1-4 and the base of FIGS. 11-16 in attached condition;

FIG. 18 is a bottom end view thereof;

FIG. 19 is a side elevational view thereof; and,

FIG. 20 is a side elevational view thereof, opposite that shown in FIG. 19.
